UNITED STATES PATENT OFFICE.

FRANKLIN BONAPARTE SHUSTER, OF NEW HAVEN, CONNECTICUT; LUELLA F. SHUSTER, ADMINISTRATRIX OF SAID FRANKLIN B. SHUSTER, DECEASED, AS-SIGNOR TO F. B. SHUSTER COMPANY, OF NEW HAVEN, CONNECTICUT, A CORPORATION OF CONNECTICUT.

WIRE STRAIGHTENING AND CUTTING-OFF MACHINE.

1,070,195.

Specification of Letters Patent. Patented Aug. 12, 1913.

Application filed August 13, 1910. Serial No. 576,969.

To all whom it may concern:

Be it known that I, FRANKLIN B. SHUSTER, citizen of the United States, residing at New Haven, in the county of New Haven and State of Connecticut, have invented certain new and useful Improvements in Wire Straightening and Cutting-Off Machines; and I do hereby declare the following to be a full, clear, and exact description of the invention, such as will enable others skilled in the art to which it appertains to make and use the same.

My invention relates to wire straightening and cutting off machines; and particularly to machines of this character constructed and adapted for straightening and cutting large stock. In straightening and cutting to length wire of small diameter the feed rolls run continuously, but with large stock, running from a half inch in diameter, or more, it is absolutely necessary to stop the feed rolls during the operation of the cutting off lever. As the wire is drawn from a coil mounted upon a reel, the rear initial feeding and preliminary straightening rolls, together with the forward feeding rolls, have a hard pull to unwind large stock from the reel and carry it through the rotary straightening arbor or roll straightener, and unless the feeding is stopped, when the cutting off lever is operated, the pressure of the incoming wire against the lever will not only retard its movement but will soon wear a groove in its face.

Referring to the drawings:—Figure 1 represents a side elevation of the machine; Fig. 2 is a reverse side of the standard supporting the feeding and straightening mechanism and broken view of the mechanism forward of the cutting off lever on line *a a* of Fig. 1. Fig. 3 is an enlarged front elevation of the machine, sectional view of the guide bar, cam shaft, and large supporting pipe on line *b b* of Fig. 1; also broken view of the cutting off lever, and broken view of the feed controlling or shifting lever on line *c c* of Fig. 5, the rest of the feeding mechanism being omitted; Fig. 4 is an enlarged broken view of the machine standard, cutting off lever, feed controlling lever and supporting pipe, and sectional view of the cam shaft on line *d d* of Fig. 3; Fig. 5 is

an enlarged broken upper plan view of the head or standard supporting the feeding and straightening mechanism; Fig. 6 is an enlarged broken detail view of a part of the tripping mechanism; and Fig. 7 is an enlarged detail side elevation of one of the rock shaft arms, sectional view of the rock shaft, apron shaft, guide bar and its apron, and sectional view of a rod in the guide bar. Fig. 8 is an enlarged broken side elevation partly in section of the cam shafts, balance wheel pulley, and sectional view of the cam for actuating the shift lever, showing the key engaged with the balance wheel pulley; and Fig. 9 is an enlarged broken view of that portion of the clutch lever adapted to engage with the key.

Like letters and figures of reference indicate like parts throughout the several views.

A description of the well known features of the machine will be briefly set forth to show the relation of my improvements thereto.

1 is the main standard or head supporting the journaled shafts 2, 3 and 4 carrying the initial straightening and feed rolls 5, 6 and 7. These roll shafts are geared together by the pinions 8, 9 and 10 shown at Fig. 5. The forward feed rolls 11 and 12, Fig. 2, are mounted on the shafts 13 and 14, which shafts are also geared together by pinions, one, 15, being shown at Fig. 5. The feed rolls are adjusted in the usual manner by means of the screws 16 and 17 and the hand wheels 18 and 19.

20 is a balance wheel pulley, formerly an ordinary driving pulley, mounted on the shaft 21 journaled in the standards 22 and 23. This shaft carries the gear 24 meshing with the gear 25 on the roll shaft 3. 26 is a sprocket wheel also mounted on shaft 3, and it carries the chain 27 to drive the sprocket wheel 28 mounted on the forward lower feed roll shaft 14, and 29 is an intermediate sprocket idler supported on the vertically adjustable standard 30.

30^a is the rotary straightener. 31 is the cutting off lever mounted on the rock shaft 32, which shaft is actuated by means of the roll 33, Fig. 3, in the lower end of said lever, engaging with the cam

groove 34 of the cam 35 mounted on the cam shaft 36 journaled in the machine head and the standard 37.

38 is the guide bar whose inner end is secured to the cutting off lever and to the free ends of the rock shaft arms 39, which arms are secured to the rock shaft 32 as shown. 40 is a smaller rock or apron shaft journaled in the upper ends of the standards 41, which standards are supported and secured on the large pipe 42. This rod 40 carries the arms 43 whose lower ends are secured to the guide bar apron 44 as seen at Fig. 3. When, therefore, the rock shaft 32 is actuated to swing the cutting off lever to sever the section of wire 44^a in the guide bar, it will also actuate the arms 39, which arms, contacting with the tail piece of the collars 45, Fig. 7, mounted on rod 40, will turn said rod to open the apron and let the severed wire section drop from the guide bar. The coiled springs 46 on rod 40 will actuate said rod in the opposite direction to return the apron to its normal position against the guide bar as soon as the cutting off lever retreats.

47 is a double arm clutch lever, Figs. 3, 4 and 5, journaled on the outer end of the rod 48, Fig. 5. The horizontal arm 47^a of this lever engages with a groove in the spring actuated key 49 to hold such key back from engagement with the balance wheel pulley 50 when the cutting off lever is stationary.

51, Fig. 1, is a gage rod which is located in the groove 52, Figs. 3 and 7, to determine the length of the wire sections to be cut off.

53 is an adjustable block secured to the outer end of the gage rod and to the trip rod 54, and 55 is a finger connected to the gage rod to which is attached one end of the trip wire 56, while the other end of this wire is attached to the lower end of the vertical arm 47^b of the clutch lever, so that, when the end of the incoming wire in the guide bar contacts with the inner end of the gage rod, the clutch lever 47 will be actuated to release the key and, by means of its spring *e*, Fig. 8, allow it to engage with the continuously running balance wheel pulley 50 and actuate the cutting off lever in the usual manner. After the clutch lever has released the key 49 it will drop in readiness for the inner face of the groove *f* of the key to engage with the incline face of the lever to force the key out of engagement with the balance wheel pulley when the shaft 36 has completed one revolution.

My present improvement consists in mechanism for temporarily halting the feeding mechanism during the operation of cutting off a section of wire, and it applies particularly to machines built expressly for straightening and cutting off large stock, for which purpose the cam 57 is mounted

on the shaft 36. 58 is a roll carried by the shift lever 59 to engage said cam. This lever is pivotally supported on the bed bracket 60 as shown.

61 is a short trip lever pivoted in the bed bracket 62, and 63 is a finger in one end of this trip lever adapted to engage with the block 64 on the end of the shift lever 59 and lock the lever in the position shown at Figs. 3, 4 and 5 while the feed rolls are in operation and the wire is being fed. When, therefore, the end of the wire contacts with the end of the gage rod in the guide bar to actuate the trip rod 54, both trip wires, viz., 56 and 65, will be actuated, the former to release the key 49 and set the cam shaft in operation as before explained, and the latter to actuate the trip lever 61 and release the shift lever and place it under the control of its retractile spring 66, which spring will cause the opposite end of the shift lever to move its sleeve 59^a toward the continuously running balance wheel pulley 20 and engage the finger 67, which finger is connected with well known clutch mechanism (not shown) which stops the feed rolls. Releasing the shift lever, as above described, will place the roll 58 of said lever against the straight face of the cam 57, and the finger 63 of the trip lever into the position shown at Fig. 6. The said roll will run against the straight face of the cam during the operation of the cutting off lever 31, and when said operation is finished the incline face 57^b will engage the roll and relock the shift lever and set the feed rolls again in operation and also bring the cutting off lever 31 to a state of rest.

Referring to Fig. 4, 68 is an arm secured to the same rod on which the clutch lever 47 is journaled, and this arm 68 carries at its lower end the housing 69 in which is located the spring pin 70 and its compression spring 71 and the spring adjusting screw 72. The spring 73, Fig. 1, on the trip rod 54, which spring is adjustably located between the collars 74 and 75 serves to reduce the strain or push for tripping the clutch mechanism to actuate the cutting off lever, and thus assist the wire when contacting with the end of the gage rod to force the weight of all the constituent parts out with but little resistance. The spring 71, Fig. 4, will force the horizontal arm 47^a of the clutch lever into engagement with the key or clutch pin 49 after the cutting off operation has been completed. By reason of the two springs acting in opposite directions, the gage mechanism can be nicely balanced by the proper adjustment of said springs.

The adjusting screw 76 in the lower end of arm 68 forms a stop for the clutch lever to allow its arm 47^a to rise just far enough to release the key or clutch pin. It also prevents any vibration of the clutch lever 130

caused by the equalizing springs 73 and 71 acting in opposite directions.

While I show my improved tripping mechanism used in connection with a rotary straightener, it is equally adapted for roll straighteners; the former is employed where round stock is straightened and cut, while the other is used for square stock.

Having thus described my invention, what I claim is:

1. In a wire straightening and cutting off machine of the character described, the combination with the wire feed rolls, guide bar and gage rod mechanism, and cutting off lever and its actuating shaft, and a continuously running balance wheel on said shaft, of a cam on said shaft, a shift lever adapted to be actuated by said cam, a continuously running balance wheel pulley for driving the feed rolls, a trip lever for locking the shift lever when the feed rolls are in operation, a clutch lever for locking the cutting off lever, trip wires connecting the trip and clutch levers so that, when the incoming

wire in the guide bar contacts with the gage 25 rod in the guide bar, both the trip lever and clutch lever will be concurrently actuated, the former to release the shift lever and stop the feed rolls, and the latter to release the cutting off lever, and means on said cam 30 for relocking the shift lever, and for relocking the clutch lever.

2. In a wire straightening and cutting off machine, the combination with wire feeding mechanism, cutting off mechanism, 35 guide bar, gage rod, tripping mechanism connected with the gage rod, of wires connecting the tripping mechanism with the feeding and cutting off mechanisms whereby both the feeding and cutting off mechanisms 40 are simultaneously actuated by the gage rod.

In testimony whereof I affix my signature in presence of two witnesses.

FRANKLIN BONAPARTE SHUSTER.
